JAMES A. PEABODY, OF EVANSTON, ILLINOIS

LOCK FOR SPRING SWITCHES

Application filed July 2, 1930. Serial No. 465,305.

This invention relates to locks for spring switches.

One object of the invention is to provide a lock for holding a spring switch in its normal position, and to prevent the clearing of a signal governing train movements in a facing direction over the switch unless the lock is effective.

Another object of the invention is to provide for releasing such a lock for spring switches to permit a trailing train movement, by employing a manually operable means which will permit the lock to become automatically effective after the train has passed over the switch.

Other objects, characteristic features, and advantages of the invention will be in part apparent, and in part pointed out, as the description progresses.

20 In the accompanying drawings, Fig. 1 illustrates in a diagrammatic and conventional manner one embodiment of the invention applied to a spring switch at one end of a passing siding, the parts and circuits being shown 25 more for the purpose of making it easy to understand the nature of the invention, than with the idea of illustrating the particular arrangement and construction preferably employed in practice; and

30 Figs. 2 and 3 are fragmentary views showing different positions of the switch lock.

The invention has been shown applied to a spring switch at one end of a passing siding for a single track railroad, which is assumed 35 to be equipped with a block signaling system of the absolute-permissive-block type, such as disclosed, for example, in the patent to S. N. Wight, No. 1,294,736, dated February 18, 1919. No attempt has been made to show the 40 complete circuits for such an A. P. B. system, there having been illustrated in Fig. 1 only some of the signal control circuits more directly related to this invention.

45 The spring switch SW, to which the invention has been shown as applied, is of the usual construction, with a front rod F, to which is connected a spring and dash pot mechanism S. The construction of this spring and dash pot mechanism S forms no part of the present invention, and is shown conventionally.

This mechanism S is of the usual well-known construction, and acts, in a manner familiar to those skilled in the art, to move the switch points to the normal or main-track position. When the switch points are trialed, and 55 moved by the wheels to the reverse position, the dash pot means serves to retard the return movement of the switch points.

The track is divided into track circuit sections in the usual way, each having a track 60 battery, and a track relay. The track section 3, adjacent the switch SW, extends back to the fouling point on the siding, the track rails being cross bonded in the usual way. The track section 4, which may or may not be used, 65 as desired, is a short track section extending back from the fouling point along the siding, so as to be occupied by the head end of a train standing on the siding back of the fouling point. The track section 2 is also a short 70 track section, approximately 800 feet long, between the absolute-starting signal 5 and the permissive approach signal 6, governing traffic from and toward the siding respectively. This track section 2 may be omitted, and the 75 starting signal 5 and approach signal 6 located opposite each other.

The circuits for controlling the absolute starting signal 5, being of the usual arrangement for an A. P. B. system, are not shown. 80 The approach signal 6, which is shown as a semaphore signal, but which may be a color-light signal, or any other suitable type, is controlled by a line or signal relay 6HD. In the form shown, this line relay 6HD is of the 85 neutral polar type, and controls the signal 6 in the usual way through a neutral contact 7 and a polar contact 8.

The signal 6 operates a circuit controller 9, shown conventionally, closed in the clear 90 and caution positions of the signal, and opened in the stop position. This circuit controller 9 is included in an energizing circuit (only partially shown) for a pole changing relay PC, which controls the polarity of the 95 current supplied to the line circuit (only partially shown), extending to the signal (not shown), next in the rear of the signal 6 and governing traffic in the same direction. When the signal 6 is in the stop position, the cir- 100

cuit controller 9 is open and de-energizes the relay PC, which reverses the polarity of energization of the line circuit to the signal next in the rear and causes that signal to indicate caution. The patent to S. N. Wight, No. 1,294,736, above mentioned, may be referred to for further details of the signaling circuits.

Considering now the lock for the spring switch SW, more particularly constituting the subject matter of this invention, a lock rod LR is connected to the front rod F of the switch SW in the usual way, and is provided with a hole to receive a lock bolt or 15 plunger LP, when the switch points are in the normal position shown, that is, when lined up for the main track. A suitable casing, not shown, supports and guides the lock rod LR, and the locking plunger LP, in the manner shown, for example, in the patent to J. E. Stephenson, No. 1,710,668, dated April 23, 1929.

The locking plunger LP is pivotally connected to the lower end of a link 10, having 25 fixed thereto a weight 11; and the upper end of the link 10 is curved and pivotally connected to a lock plate 12. This lock plate 12 is fixed to a shaft 13, supported in suitable bearings and having fastened thereto an 30 operating crank or handle 14. The shaft 13 (indicated in part by dash lines) operates circuit controller drums or segments 15 and 16, co-operating with pairs of contact fingers 17 and 18, said circuit controller drums having insulated portions, so as to break the circuits through the contact fingers 17 and 18 in 35 certain positions of the shaft.

A lock plate 12 is formed with a shoulder 12¹ for co-operating with a lock dog 19 carried by the pivoted armature 20 of an electro-magnet 21. This lock dog 19 is preferably arranged so that it can be released by hand, if necessary.

These parts of the lock are supported and 45 housed in a suitable casing, in the manner shown, for example, in the patent to J. E. Stephenson above mentioned; and the door 22 (shown diagrammatically) for this casing, giving access to the handle 14, is provided with the usual hasp and padlock, and is also formed with a recess 22¹, or provided 50 with equivalent lugs or the like, so that the door cannot be closed and locked, unless the handle 14 is in the positions shown in Figs. 55 1 and 3.

When the lock and plunger LP is in the hole of the lock rod LR, and thus locks the spring switch SW in its normal position, the parts are in the position shown in Fig. 1. 60 Under these conditions, the relay 6HD, controlling the signal 6, may be energized over a circuit, which may be traced from C (indicating a connection to a common return wire), relay 6HD, wire 23, front contact 24 of track relay T-2, wire 25, front contact 26 of track

relay T-3, wire 27, contacts 28 of the usual switch circuit controller connected to the switch points of the switch SW, wire 29, contact fingers 17, wire 30, and thence through various other controlling contacts (not 70 shown), to B (indicating a connection to a suitable source of current connected to the common return wire).

Thus, if the switch SW is locked, the approach signal 6 may clear.

If, for any reason, the locking plunger LP does not fully enter the hole of the lock rod LR, the lock plate 12 is displaced from the position shown in Fig. 1 sufficiently to open the circuit for the relay 6HD at the contact fingers 17. Consequently, if the switch SW is not properly locked, the signal 6 is held in the stop position, and the signal next in the rear (not shown) indicates caution.

Before a train can trail the spring switch SW, the lock must be disengaged. Considering a train movement off of the siding, the trainman goes to the switch, unlocks and opens the door 22, and moves the handle 14 counter-clockwise from the position shown in Fig. 1 to the position shown in Fig. 2, disengaging the locking plunger LP from the lock rod LR. In this extreme unlocked position of the handle 14, the upper end of the link 10 is moved beyond the dead central position, as shown in Fig. 2, so that the handle 14 need not be held to hold up the weight. In order that the trainman may know whether or not any train is approaching, a switch indicator SI is preferably used. This switch indicator SI is controlled in accordance with established practice, in the manner such as shown for example, in the patent to S. N. Wight, No. 1,224,111 dated April 24, 1917.

This movement of the handle 14 and shaft 13 to the unlocked position shifts the circuit controller drum 16 to connect the contact fingers 18, which are included in an energizing circuit for the electro-magnet 21 which may be traced from (+) (indicating a connection to one terminal of a suitable local battery), electro-magnet 21, wire 31, contact fingers 18, wire 32, front contact 33 of track relay T-4, wire 35, front contact 36 of track relay T-3, to (-).

Assuming the use of the short track section 4, the presence of the head end of the train standing on the siding shunts the track relay T-4, and opens the energizing circuit 110 for the electro-magnet 21, so that the lock dog 19 is in the position, as shown in Fig. 2, to engage the locking shoulder 12¹. If the track circuit section 4 is not used, as soon as the train moves into the track circuit section 3, and shunts the track relay T-3, the energizing circuit for the electro-magnet 21 is broken at the front contact 36.

In either case, the trainman may set the handle 14 and the plate 12 to the position

shown in Fig. 3, where the upper end of the link 10 is not on dead center, and the weight 11 tends to move the lock plunger LP down into its locking position, this movement being prevented by the engagement of the lock dog 19 with the shoulder 12¹. The trainman may now close and lock the door 22; and after the train has cleared the switch SW, the electro-magnet 21 is energized, and releases the plate 12, so that as soon as the switch points are returned to the normal position by the spring and dash-pot mechanism S, the lock plunger LP may enter the hole in the lock rod LR and lock the switch points in this position. If the switch SW should not be locked up automatically in this way, the signal 6 cannot clear, as above explained.

From the foregoing it can be seen that a simple and efficient manually operable lock for a spring switch is provided by this invention, which permits train movements in the facing direction safely at normal running speeds, since the switch points must be positively locked in the normal position before the signal 6 can be cleared for such train movements. Also, the lock for the spring switch may be easily unlocked manually, when it is necessary to trail the switch. After such manual unlocking, the trainman does not have to wait until the train has cleared the switch and then manually lock up the switch again, but may condition the locking device so that it will be automatically locked as soon as the train has cleared the switch. This makes it unnecessary for the train to slow down or stop, after having cleared the switch, in order that the trainman may get aboard after having locked up the switch.

The spring switch SW is preferably provided with the usual hand-throw device or switch stand 40, so that the switch points may be reversed to permit a train to enter the siding.

The specific construction and arrangement of parts and circuits, diagrammatically illustrated in the accompanying drawings, represents merely one typical embodiment of the invention; and various additions, modifications, and adaptations may be made in this specific embodiment, without departing from the invention.

What I claim is:

1. In a locking device for railway spring switches, the combination with the movable switch points of a track switch, spring means tending to move said switch points to the normal position, a signal governing train movement in the facing direction over said switch, a manually controllable lock biased to its locking position for positively holding said switch points in their normal position, electrically operable track circuit controlled means for holding said lock in its

unlocked position in opposition to its bias, and means preventing clearing of said signal while said lock is unlocked.

2. In a locking device for railway spring switches, the combination with the movable switch points of a track switch, spring means tending to move said switch points to the normal position, a lock rod connected to said switch points, a locking plunger for locking said lock rod in the position corresponding to the normal position of the switch points, means tending to move said locking plunger to its locked position, electrically operable means for holding said locking plunger in its unlocked position, a circuit controller connected to said locking plunger and closed only if said plunger is in its locking position, manual means for moving said locking plunger to its unlocked position, a signal governing traffic in the facing direction over said switch, and a controlling circuit for said signal including said circuit controller.

3. In a locking device for railway spring switches, the combination with the movable switch points of a track switch, spring means tending to move said switch points to the normal position, a manually controllable lock for holding said switch points in their normal position, said lock being biased to assume its locking position, and track circuit controlled means for retaining said lock in its unlocked position in opposition to its bias while a train is passing over the switch.

4. In a locking device for railway spring switches, the combination with the movable switch points of a track switch, spring means tending to move said switch points to the normal position, a lock biased to assume its locking position for positively locking said switch points in their normal position, a locking electro-magnet acting when de-energized to hold said lock in its unlocked position, and a track circuit adjacent the switch for controlling said electro-magnet to permit energization thereof when said track circuit is not occupied.

5. In a locking device for railway spring switches, the combination with the movable switch points of a track switch, spring means tending to move said switch points to the normal position, a plunger lock biased to assume its locking position for holding said switch points in their normal position, electrically operated means for holding said lock in its unlocked position in opposition to its bias, and circuit controlling means operated by said lock for controlling the energization of said electrically operable means.

6. In a locking device for railway spring switches, the combination with the movable switch points of a track switch, spring means tending to move said switch points to the normal position, a lock rod connecting to the

switch points, a weighted locking plunger engageable with said lock rod to lock said switch points in their normal position, a track circuit adjacent the switch, and electrically operable means controlled by said track circuit means and by the position of said locking plunger for holding said locking plunger in its raised unlocked position.

7. Apparatus for governing the movable switch points of a track switch for railroads comprising, a lock rod connected to the switch points, a manually operable locking plunger engageable with said lock rod to lock the switch points in one extreme position, and electrically releasable means for holding said locking plunger in its unlocked position after it has been manually moved to that position.

8. A protective device for track switches on railroads comprising, a lock rod connected to the switch points, a locking plunger biased to assume its locking position and engageable with said lock rod only when said switch points are in the normal position for locking said switch points against movement, and an electrically releasable locking device for holding said locking plunger in its unlocked position in opposition to its bias.

9. In a device of the character described, a lock rod adapted to be connected to the movable switch points of a track switch, a locking plunger adapted to enter a hole in said lock rod when said switch points are in one extreme position and thereby lock said switch points against movement, means tending to move said locking plunger to its locking position, manually operable means for moving said locking plunger to its unlocked position, and an electric lock for holding said locking plunger in its unlocked position after it has been manually moved to that position.

10. In a safety device for track switches on railroads, a plunger lock biased to assume a locking position for locking the switch points in a normal position, manually operable means for shifting said plunger lock to its unlocked position, an electric lock for preventing movement of said plunger lock to its locking position, said electric lock being released when energized, and track circuit controlled means for energizing said electric lock only if a portion of the track adjacent said switch is not occupied by a car.

11. A controlling device for track switches on railroads comprising, spring means operatively connected to the switch points and tending to move said points to the extreme normal position, a lock rod connected to the switch points, a manually operable locking plunger engageable with said lock rod to lock said switch points only in the normal position, a locking device for preventing movement of said plunger to its locked position, and electrically operable means for releasing said locking device.

12. A locking device for track switches on

railroads comprising, a lock rod adapted to be connected to the switch points, a manually movable locking plunger co-operating with said lock rod only when the switch points are in the normal position to hold said switch points against movement, means tending to move said locking plunger to its locking position, and track circuit controlled means for positively preventing movement of said locking plunger to its locking position while a train is passing over the switch.

13. A locking device for track switches on railroads comprising, a lock rod adapted to be connected to the switch points, a locking plunger for locking said lock rod against movement only in one extreme position corresponding to the normal position of the switch points, biasing means tending to move said plunger to its locked position, manually operable means capable of moving said plunger to an unlocked position in which it is held or to an unlocked position in which said biasing means is effective, and an electric lock for positively preventing movement of said locking plunger to its locking position.

14. Apparatus for governing the movement of track switches on railroads comprising, a lock rod adapted to be connected to the switch points, a manually operable mechanical locking device positively holding said lock rod in one extreme position, means tending to move said locking device to its locking position, an electric lock acting when de-energized to prevent said locking device assuming its locking position, and circuit controlling means included in the energizing circuit for said electric lock and closed only if said locking device is in its unlocked position.

15. A safety device for track switches on railroads comprising, in combination with spring means adapted to be connected to the switch points and capable of moving said switch points to one extreme position unless otherwise restrained against movement, a mechanical lock for positively holding the switch points in said extreme position, manually operable means for releasing said lock, electrically operable means acting when de-energized to prevent said lock assuming its locking position after having been manually unlocked, and a circuit controller included in the energizing circuit for said electrically operable means and closed only when said lock is in its unlocked condition.

16. A safety device for track switches on railroads comprising, a lock rod adapted to be connected to the switch points, a locking plunger engageable with said lock rod in one extreme position only to lock the switch points against movement, biasing means tending to move said plunger to its locking position, electrically operable means for holding said plunger in its unlocked position in opposition to said biasing means, manually oper-

able means for moving said locking plunger into position to be held by said electrically operable means, circuit controlling contacts operated in accordance with the position of said plunger, a track circuit adjacent the switch and having a track relay, and a control circuit for said electrically operable means governed by said contacts and by said track relay.

10 In testimony whereof I affix my signature.

JAMES A. PEABODY.
